UNITED STATES PATENT OFFICE.

GEORGE M. ANDERSON, OF WASHINGTON, DISTRICT OF COLUMBIA.

RUBBER TREAD FOR BOOTS AND SHOES.

1,281,476.

Specification of Letters Patent. Patented Oct. 15, 1918.

Application filed July 25, 1917. Serial No. 182,683.

To all whom it may concern:

Be it known that I, GEORGE M. ANDERSON, a citizen of the United States, resident of Washington, in the District of Columbia, 5 have made a certain new and useful Invention in Rubber Treads for Boots and Shoes; and I declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 Figure 1 is a central vertical cross section of the invention.

Fig. 2 shows in detail perspective view the plug, the metal backing and the rubber member.

20 Fig. 3 is a central vertical section of a modification.

Fig. 4 is a detail perspective view of the modified metal backing.

The invention has relation to rubber heels 25 wherein are used hollow friction plugs, wound from a strip of rubber-coated or frictionized canvas, said plugs vulcanized to the body of the heel, the object of the invention being to dispense with either interior or exterior metallic or post retaining 30 means for the hollow plugs, and to provide in substitution therefor improved retaining means for the plug.

The invention consists in the novel construction and combinations of parts, as hereinafter set forth.

In the accompanying drawings, illustrating 40 the invention, the numeral 2 designates a rubber heel, 3 a backing, usually of circular form and of perforated metal, and 4 the plug, engaged within a recess of the heel, wound from a strip of frictionized canvas or other suitable rubber-coated material and provided with a central perforation 5.

45 The fastening nail 3' has its head engaged within the perforation of the hollow plug and its shank engaged with the central portion of the backing. The perforation of the backing is of smaller size than that of the 50 hollow plug, and is provided with a marginal portion overlying the top of the perfora-

tion of the plug and adapted to be engaged by and back up the head of the nail.

6 is a member made of soft rubber of the best grade and located upon the top of the 55 plug 4, between the same and the backing 3, the shank of the nail 3' passing through the center of the rubber member as well as through the backing.

In the manufacture of the heel, the rubber 60 material of the member 6 will vulcanize perfectly with the rubber constituent of the plug, and will also closely adhere to the lower face of the backing and even flow within the perforation of the backing and 65 around the peripheral edge thereof, so that the plug will be as securely held in the heel as is the backing itself by the fastening nail.

A modification of the invention is shown 70 in Figs. 3 and 4 of the drawings, wherein the metal backing 3² is shown as also having perforation 7, located between the central perforation 7' thereof and the edge of the backing, the object being to allow the rubber of the member 6 to flow also within these 75 additional perforations, for better locking effect.

I claim:

1. In a rubber tread for boots and shoes, 80 having a recess, a hollow friction plug of rubber-containing material located within said recess, backing means overlying said plug, a rubber member located intermediate of said plug and said backing means and vulcanized to said plug and incorporated with said backing means, and a fastening nail the head of which engages the hollow of said plug and the bottom of 85 said backing means and the shank of which passes through the central portion of said 90 backing means.

2. In a rubber tread for boots and shoes having a recess opening into its tread face, a friction plug of rubber containing material located in said recess, and a rubber bonding member located between a wall of 95 said recess and said plug, and incorporated with both the plug and the material of the heel.

3. In a rubber tread for boots and shoes 100 having a recess opening into its tread face, a friction plug of rubber containing material

located in said recess, and a rubber bonding member overlying the plug and located between the same and the top wall of said recess, said member vulcanized and in-
5 incorporated with both the material of the plug and the material of the heel.

In testimony whereof I affix my signature in presence of two witnesses.

GEORGE M. ANDERSON.

Witnesses:

W. R. BAUM,
STUART HILDER.
